(57) **CLAIM**

The ornamental design for an insert for finger ring of shears, as shown and described.

DESCRIPTION

FIG. 1 is a front elevational view of the insert for finger ring of shears as used in a pair of shears;

FIG. 2 is an isometric view of the insert for finger ring of shears;

FIG. 3 is a front elevational view of the insert for finger ring of shears;

FIG. 4 is a back elevational view of the insert for finger ring of shears;

FIG. 5 is a left elevational view of the insert for finger ring of shears; and,

FIG. 6 is a right elevational view of the insert for finger ring of shears.

The broken line showing of the shears in FIG. 1 illustrates the environment of the claimed design and forms no part thereof.
